UNITED STATES PATENT OFFICE

MICHAEL J. KREUTZER, OF DAYTON, OHIO

BOTTLE-WASHING APPARATUS

Application filed October 17, 1928. Serial No. 313,090.

This invention relates to improvements in bottle-washing apparatus.

The primary object of this invention is the provision of apparatus for quickly and efficiently washing bottles which merely necessitates the inverting of the bottle and placement upon the apparatus, with a natural down pressure, so as to cause the opening of a pressure regulated valve; permitting the cleansing fluid to enter the bottle and wash the same, and upon release of the manual pressure the valve being closed by the pressure of the cleansing liquid.

A further object of this invention is the provision of an improved pressure regulated valve in connection with my bottle washing apparatus set forth in Patent #1,667,597 granted to me April 24, 1928.

A further object of this invention is the provision of improved bottle washing apparatus which may be used in connection with an ordinary household fountain; being attachable or detachable with respect thereto quickly, and including a valve which is ordinarily closed by pressure of the liquid passing from the faucet, but which may be opened by natural manual pressure as the bottle or other article is brought into position upon the apparatus for cleansing.

Other objects and advantages of this invention will be apparent during the course of the following detailed description.

In the accompanying drawing, forming a part of this specification, and wherein similar reference characters designate corresponding parts throughout the several views,

Figure 1 is a cross sectional view taken through the improved bottle washing apparatus, showing a bottle in position for washing and the attachment of the apparatus to a water faucet.

Figure 2 is a fragmentary sectional view of details of the bottle washing apparatus shown in Figure 1, but with the pressure operated valve in a closed position.

Figure 3 is a cross sectional view taken substantially on the line 3-3 of Figure 1.

Figures 4, 5, 6 and 7 are details of the improved pressure regulated valve and its attaching and mounting parts.

In the drawing, wherein for the purpose of illustration is shown but a preferred embodiment of the invention, the letter A may generally designate the improved bottle washing apparatus, which may include a body B, having an improved valve C mounted by means D upon a faucet or other member F so that the water passing through the latter may operate upon said valve C or pass the same into the body B. The latter is provided with means for supporting a bottle K thereon in an inverted position for washing.

The body B may be of any approved material, and preferably comprises a cylindrical chamber 10 entirely open at the top thereof for receiving means E. The body B furthermore includes a downwardly tapered bottom 11 converging to a lower opening which is relatively restricted. An outlet tube or conduit 14 is laterally connected with the portion 10 of the body B, for permitting the liquid to pass therefrom after the bottle has been washed, and a screen 15 may cooperate over this if found necessary inasmuch as small granulated members or shot 16 are placed in the body B to assist in the cleansing operation, as will be subsequently mentioned.

The means E is more specifically set forth in my patent above referred to, and comprises a supporting portion 18 having a reduced shank 19 adapted to fit in the top opening of the chamber 10 of the body B, and being provided with a spider 20 in the chamber 10 which vertically supports a tube or elongated nozzle 21.

The nozzle 21 is provided with a passageway 23 therethrough, thru which water and the shot 16 may pass. The tube or nozzle 21 at its lower end is flared at 25, and faces the lower open end of the body B, in annular spaced relation with the tapered walls 11 of the body B, so that the shot may readily enter the same. The nozzle 21 extends vertically upward, above the means E. In the support 18 is provided

a resilient bushing 30, into which the neck 31 of the bottle K may be inserted, when the bottle K is inverted, in order to position the tube or nozzle 21 in the neck portion of the bottle, so that the cleansing liquid and shot 100

may readily pass upwardly into the bottle for cleansing the same.

The means D preferably comprises an elbow 35, in right angled formation, having a passageway 36 therethrough and at its upper end being internally screw threaded at 37. At its opposite end it is connected with a second right angled elbow 38, and therewith forms a U-shaped connection. A swivel connection 39 is used to connect the elbow 38 with the nozzle F, in such relation that the screw threaded opening 37 faces and opens vertically upward.

A bushing or valve seat 40 is screw threaded into the opening 37, having an upper polygonal shaped wrench engaging head 41 thereon, and internally having a passageway 42 adapted to snugly and slidably receive the valve member 44 constituting part of the valve structure C. This seat 40 is provided with a downwardly facing tapered or beveled valve seat 45, which is beveled in a downwardly divergent relation, for seating cooperation with the valve body 44.

The valve member or body 44 is elongated, having a reduced axial passageway 47 therethrough, which terminates short of the lower surface 48 of the body 44, and is laterally intersected by a pair of diametrical ports 49, 50 in right angled relation, which open exteriorly upon the valve body, as shown in Figures 3 and 6 of the drawings, and elsewhere. At its lower end the valve member 44 is provided with a bevel flanged end 50 of a nature to seat on the bevel surface 45 of the valve seat 40, to close off communication of the ducts 49 from the passageway 36 of the connection D, as is shown in Figure 2 of the drawing, and in which case the lower surface 48 of the valve member is flush with the plane of the lower edge of the valve seat 40. The valve member 44 inwardly from the upper end thereof is provided with a screw threaded socket 58, which is adapted to detachably receive a screw threaded shank 59 of a special nut 60, with which to connect the body B of the washing apparatus to the valve structure. This special nut 60 is provided with a frusto-conical hollow body portion 61, adapted to fit within the lower tapered end of the body B, in wall fitting engagement therewith; the body 61 having a tapered chamber 62 therein which downwardly converges into communicating relation with a restricted passageway 64 disposed axially through the screw threaded shank 59 and opening at the lower end thereof. The shank 59 when screw threaded in the socket 58 alines the passageways 47 and 64, and the upper end of the passageway 64 is restricted sufficiently that the shot 16 cannot fall downwardly thereinto.

A hollow frusto conical washer or centering piece 65 is provided, within which the lower tapered end of the sloping wall 11 of

the body seats, when the nut 60 is threaded into the valve member 44 as above described, and as shown in Figure 1 of the drawing.

It should be noted that in the position of parts when assembled, the lower edge 67 of the seating piece 65 is in abutment with the top edge 68 of the valve member 44, and the tapered socket 70 therein snugly receives the lower tapered end of the body B; the nut 60 being adjusted, at its screw threaded shank, into the valve member 44 to draw the tapered portion 61 snug within the lower tapered end of the body B. In this position of parts there is no chance for escape of liquid and the valve member is firmly connected to the body B, but in a detachable relation. The length of the valve member 44 above the duct 49 is greater than the axial length of the valve seat 40, so that the valve member may reciprocate in the valve seat and move downwardly to expose the ducts or ports 49 to the chamber 36 for passage of water thereinto and upwardly through the body B in a bottle washing relation. As an incident of pressure of the cleansing fluid when the valve of the faucet F is opened, the water may act on the surface 48 and force the valve member 44 to a position where the tapered end 50 seats in the bevel seating surface 45 of the valve bushing 40, to close the ducts 49 so that none of the cleansing fluid can enter the same and pass into bottle washing relation through the body B.

In the operation of the invention the bottle K is placed in the resilient bushing 30 and the upper end of the nozzle 21 of course enters the bottle and upon manually pressing the bottle down the body B is moved and the valve member 44 therewith to open the valve and permit water from the faucet F, the valve of which has already been opened, to enter the valve member 44 and pass upwardly therethrough and through the restricted passageway 64 of the special nut 60. The water entering the body B discharges forcibly against the shot 16, sending part of the same upwardly through the long nozzle tube 21 into bottle cleansing relation in a manner which is perfectly obvious.

Various changes in the shape, size, and arrangement of parts may be made to the form of invention herein shown and described, without departing from the spirit of the invention or the scope of the claim.

I claim:

In a device of the class described, a bottle supporting and washing device including a casing with a downwardly tapered wall, a frusto-conical washer having a tapered socket for receiving the end of the tapered wall therein, an elongated valve member having a passageway therethrough, a special nut threaded in said valve member and engaged within the tapered wall to clamp the same in said tapered socket with the valve member

drawn tight thereagainst, the special nut having a passageway therethrough opening into the passageway of said valve member, a valve seat of tubular formation slidably receiving the valve member therethrough, the valve member having lateral ducts to the passageway therein which may be closed or opened by sliding the valve member in said seat.
